DIE PUNCH

Jacob A. Smith, Chicago, Ill., assignor of one-half
to Claude A. Benjamin, Chicago, Ill.

Application June 5, 1942, Serial No. 445,841

9 Claims. (CL. 164—124)

This invention relates to die punches and more particularly to punches adapted to be used with piercing dies and to means to remove the punches for repair or replacement.

Heretofore die punches have been supported in piercing dies by rigidly connecting the punch to the die pad. In the event of damage to the punch, it was necessary to remove the entire die pad for replacement of the damaged punch. It has also been proposed removably to support punches in holders connected to the die pad in which constructions a relatively loose mounting of the punch has been required resulting in a loss of accuracy.

One of the objects of the present invention is to provide a die punch accurately supported on a die pad and readily removable therefrom for replacement.

Another object of the invention is to provide a tool for removing die punches operable at a distance from the punch.

Another object of the invention is to provide a tool for removing die punches which does not place a strain on the punch holder or quill.

Still another object of the invention is to provide a tool for removing die punches which is operable quickly and easily yet which develops a high degree of force to remove the punch from the holder.

A further object of the invention is to provide a tool for removing a die punch including means providing a rapid motion to take up slack and high leverage motion to provide the final operating movement.

The above and other objects and advantages of the invention will be apparent from the following description when read in connection with the accompanying drawing, in which—

Figure 1 is a partial section of a punch mounting embodying the invention;

Figure 2 is a side elevation of a tool for removing the punch;

Figures 3, 4 and 5 are sectional views of the tool illustrating its manner of use; and

Figure 6 is a partial section on the line 6—6 of Figure 4.

Figure 1 illustrates a die including a block 10 on which a pad 11 is mounted. The pad is formed with a series of holes 12 to receive punch holders or quills 13 which may be accurately located in the holes 12 and held therein by enlarged upper end portions 14.

The quills 13 are formed at their outer ends with tapered openings 15 to receive tapered shanks 16 of punches 17. The upper ends of the shanks 16 extend into transverse slots 18 in

the quills. By this construction, the quills may be accurately rigidly and permanently mounted in the die pads while the punches are securely and accurately mounted in the quills.

5 In order to remove a punch from its quill in the event of damage to the punch, a tool is provided comprising an elongated tube 19 having a transverse bore 21 therein to receive the quill. The tube 19 may be made of any desired length so that an operator can reach into a large die to replace a punch therein without difficulty. A wedge 22 is slidable in the tube 19 and terminates in a flattened wedge shape portion to enter the slots 18 and engage the upper end of the shank. 10 The wedge may be held against rotation in the tube by means such as a threaded plug 23 in the side of the tube engageable with the wedge.

The tube 19 is secured to a block formed of side plates 24 connected by end plates 25 and 26. The side and end plates may be integrally or separately formed but preferably each side plate is integral with one of the end plates so that the block is formed by two L-shaped pieces. The plate 25 is formed with a bore to receive the tube 15 which may be held against movement outwardly of the block by a shoulder 27 engaging the end plate. The wedge 22 extends beyond the shoulder 27 and terminates in an enlarged end 28 which is urged inwardly of the block by a coil spring 29.

20 The head 28 on the wedge engages a cam 31 shown as formed by an enlarged cylindrical boss supported on pins 32 and having a flattened cam face 33 on one side thereof to engage the head. The pins 32 are slidably and rotatably supported in elongated slots 34 in the side plates 24 and the cam is adapted to be turned by a hand lever 35 secured thereto. The position of the pins in the slots may be determined by a screw mechanism for advancing the cam to take up loose motion. 25 This mechanism, as shown, comprises a screw 36 threaded into an end plate 26 and having a knurled knob 37 at its outer end.

30 In operation, when it is desired to remove a punch from a quill, the opening 21 in the tube 19 is slipped over the quill with the parts in the position shown in Figure 3. The tube is adjusted angularly and longitudinally of the quill until the end of the wedge 22 is aligned with the slot 18 and the screw 36 is then turned until the wedge engages the end of the shank 16 as shown in Figure 4. During this movement, the cam is not turned but is moved bodily in the block by engagement of the screw 36 therewith. Thereafter, the lever 35 may be swung counter-clockwise as shown in Figure 5 to force the

wedge 22 forwardly with a high leverage. This final increment of movement which may be relatively small will cause the wedge to move the shank downwardly in the quill to loosen it therefrom so that it may drop out freely.

In addition to the ease of removal and replacement of punches as explained above, the present construction has the additional advantage of economy of manufacture. Because of the fact that only the small punches II need be made of high grade expensive steels while the quills may be made of low grade less expensive materials the cost of punches over conventional punches which had to be made of high grade steel throughout is materially reduced. Furthermore, since only the small punch part II need be replaced in the event of wear and breakage, the cost of maintaining the punches in proper operation is kept at a minimum.

While one embodiment of the invention has been shown and described in detail, it will be understood that it is illustrative only and is not intended as a definition of the scope of the invention, reference being had for this purpose to the appended claims.

What is claimed is:

1. A tool for use with a tool holder having a pad, comprising a quill carried by the pad having a tapered opening at its outer end and a transverse slot intersecting the opening, a tool having a tapered shank fitting in the opening with the end of the shank extending into the slot, in combination with a tool for removing the punch from the quill comprising an elongated supporting member to engage and hold the quill and a wedge slidably longitudinally of the supporting member to enter the slot and force the tool from the quill.

the quill.

2. A die punch for use with a die having a pad, comprising a quill carried by the pad having a tapered opening at its outer end and a transverse slot intersecting the opening, a punch having a tapered shank fitting in the opening with the end of the shank extending into the slot, in combination with a tool for removing the punch from the quill comprising an elongated tube having a transverse opening to receive the quill, a wedge slideable in the tube to enter the slot and engage the end of the punch shank, and means to move the wedge in the tube.

3. In a die punch having a quill with a tapered end opening to receive a tapered shank on a punch, a punch removing tool comprising an elongated support to engage the quill, a wedge slidable longitudinally of the support to enter a slot in the quill and engage the punch shank, low leverage means to move the wedge into engagement with the shank, and higher leverage means thereafter to give the wedge an additional increment of movement.

4. In a die punch having a quill with a tapered

end opening to receive a tapered shank on a punch, a punch removing tool comprising an elongated support to engage the quill, a wedge slideable longitudinally of the support to enter a slot in the quill and engage the punch shank, a cam movable relative to the support to engage and move the wedge, and some means to move the cam.

5. In a die punch having a quill with a tapered end opening to receive a tapered shank on a punch, a punch removing tool comprising an elongated tube having a transverse opening therein to receive the quill, a wedge slidable in the tube to enter a slot in the quill and engage the punch shank, and means connected to the tube to engage and move the wedge therein.

6. In a die punch having a quill with a tapered end opening to receive a tapered shank on a punch, a punch removing tool comprising an elongated tube having a transverse opening 20 therein to receive the quill, a wedge slideable in the tube to enter a slot in the quill and engage the punch shank, low leverage means to move the wedge in the tube until it engages the shank, 25 and higher leverage means thereafter to give the wedge an additional increment of movement.

7. In a die punch having a quill with a tapered end opening to receive a tapered shank on a punch, a punch removing tool comprising an elongated tube having a transverse opening therein to receive the quill, a wedge slidable in the tube to enter a slot in the quill and engage the punch shank, a block connected to the tube, a cam rotatably and slidably carried by the block and engaging the wedge to move it, and a screw in the block engaging the cam to slide it in the block.

40 8. A tool holder including a quill having a tapered opening at its outer end and a transverse slot intersecting the opening, a tool having a tapered shank fitting in the opening with the end of the shank extending into the slot, in combination with means for removing the tool from the quill comprising an elongated supporting member to engage and hold the quill and a wedge slideable longitudinally of the supporting member to enter the slot and force the tool from the quill.

50 9. A tool holder including a quill having a tapered opening at its outer end and a transverse slot intersecting the opening, a tool having a tapered shank fitting in the opening with the end of the shank extending into the slot, in combination with means for removing the tool
55 from the quill comprising an elongated tube having a transverse opening to receive the quill, a wedge slidable in the tube to enter the slot in the quill and engage the end of the tool shank, and means to move the wedge in the tube.

JACOB A. SMITH.
